UNITED STATES PATENT OFFICE.

LANGDON S. BARRON, OF ST. LOUIS, MISSOURI, ASSIGNOR OF ONE-HALF TO BENJAMIN RICHTER, OF ST. LOUIS, MISSOURI.

SHOE HEEL.

1,424,975.

Specification of Letters Patent. Patented Aug. 8, 1922.

Application filed April 30, 1921. Serial No. 465,948.

To all whom it may concern:

Be it known that I, LANGDON S. BARRON, a citizen of the United States, residing at St. Louis, State of Missouri, have invented 5 certain new and useful Improvements in Shoe Heels, of which the following is a specification.

My invention has relation to improvements in shoe-heels, more particularly to the 10 fastening devices whereby the heel is secured to the shoe, and consists in the novel details of construction more fully set forth in the specification and pointed out in the claims.

15 Heretofore, so far as I am aware, heels (both metallic and non-metallic) have been secured to the shoe by a plurality of nails, which are cast into the metal heels, or by screws. It is the object of the present invention to dispense with nails and screws 20 as fastening means, and substitute therefor suitable cooperating devices on the heel and shoe that may be pressed into engagement and effectively lock the heel to the 25 shoe. A further object is to provide complementary fastening devices on the heel and the shoe that operate by wedging action, one member being expanded within the other. Further and other advantages will 30 be better apparent from a detailed description of the invention in connection with the accompanying drawings in which—

Figure 1 is a side elevation of a shoe with my improved heel applied, parts being 35 broken away; Fig. 2 is a middle vertical section through the heel; Fig. 3 is a front elevation of the heel; Fig. 4 is a top plan of the same; Fig. 5 is a bottom plan of the heel plate; Fig. 6 is an enlarged section through 40 the fastening devices on the heel and the plate; Figures 7 and 8 are middle vertical section and top plans respectively of a heel provided with a modified form of fastening devices; Figs. 9 and 10 show a still further 45 modified form of the fastening device of the shoe, said device being fixed to a washer; Fig. 11 is a plan view of a reinforcing strip with the fastening devices secured thereto instead of being on a separate plate.

50 Referring to the drawings, and for the present to Figures 1 to 6 inclusive, S represents a ladies' shoe having an outsole 1, insole 2, metallic stiffening strip 3, and heel H, preferably of aluminum. The heel is 55 cast hollow and is provided with a lift L

secured against the lower face of the bottom wall 4. The parts thus far described are old in the art. However, the heel must be securely fastened to the heel seat of the shoe and it is to this fastening means that my 60 invention is directed. Projecting upwardly from the inside of the heel shell are a series (in the present case three) of bosses 5, preferably cast integral with the heel, although they could be otherwise secured; and in the 65 case of a wood or leather heel they would have to be individual members secured to the heel in any desirable manner. The bosses 5 are substantially cylindrical and each is provided with an annular recess 70 the wall *a* of which is upwardly inclined. The formation of the recess 6 leaves a conical wedge 7 projecting upwardly at the center of the boss 5. The bosses 5 constitute the fastening members on the heel. Complementary fastening members are provided on 75 the shoe as follows:

A metallic plate 8 is inserted in the shoe sole between the stiffening strip 3 and inner sole 2, said plate being provided with a series of bosses 9 projecting downwardly through openings 10 in the outer sole 1. The bosses 9 are provided with longitudinal kerfs 11, disposed at right angles to each other, thereby dividing the boss into four 85 fingers 12.

In securing the heel to the shoe it is merely necessary to clamp the heel in a vise and position the bosses 9 over the bosses 5, whereupon the proper amount of pressure 90 exerted within the heel of the shoe will force the bosses 9 into the recesses 6. As soon as the boss 9 begins to enter the recess 6 the wedge 7 will enter at the intersection of the kerfs 11 and spread apart the fingers 12. 95 The fingers will be spread the whole while they are entering the recess 6, the wedge 7 maintaining said fingers in contact with the wall *a* of the recess. From the above it is apparent that the bosses 9 are tightly 100 wedged into the recesses 6 and the heel is securely fastened to the shoe. Of course, the depth of the kerfs 11 and recess 6 should be such that the upper edge *e* of the heel will fit snugly against the heel seat of the 105 shoe before the fingers 12 strike the bottom of the recesses 6. In practice sufficient allowance should be made so that there will always be some clearance between the fingers and the bottom of the recesses.

The lift L has a metallic plate 13 imbedded in it, said plate being provided with a kerfed boss similar to the bosses 9, and the wall 4 of the heel is provided with a recess 5 and wedge 16 similar to recess 6 and wedge 7. In fastening the lift to the heel the latter is securely held in a vice whereupon a single blow with a hammer is sufficient to wedge the boss 14 into the recess 15.

10 While the preferred form of fastening devices is as shown in Figures 1 to 6 still I may modify the shape of the bosses as shown in Figures 7 and 8. Here I show three bosses 9' projecting from the heel instead of the shoe while the bosses 5' are on the shoe. The bosses 9' and 5' are rectangular and 9' has but two fingers 12' and bosses 5' have complementary recesses 6' separated by a flat wedge 7'. Instead of the bosses 9

15 being secured to a plate of the size of the heel seat I may secure them to washers or disks 17 to be placed in the shoe as shown in Figures 9 and 10, or I may secure them directly to the reinforcing strip 3 as shown

20 in Fig. 11.

25 Obviously a great number of modifications might be devised that would fall within the spirit of my invention, and I do not wish to be restricted to the particular forms shown herein.

Having described my invention, I claim:

1. A hollow shoe-heel having a boss projecting upwardly from the inner surface thereof, said boss being provided with a recess and a wedge, and a boss projecting

downwardly from the heel seat of the shoe, the last mentioned boss being kerfed so as to divide it into a series of fingers, said wedge operating to bind the fingers into the recess on forcing the bosses into engagement 40 thereby securing the heel to the shoe.

2. In combination with a shoe and heel therefor, a set of securing devices formed in the upper surface of the shoe heel, and a set of complementary securing devices projecting downwardly from the heel seat of the shoe, one of said sets of securing devices being provided with recesses having inclined walls, the other set having fingers with parallel sides adapted to be wedged into the 45 aforesaid recesses, for securing the heel to the shoe.

3. In combination with a shoe and heel therefor, a securing device formed in the upper surface of the shoe heel, and a complementary securing device projecting downwardly from the heel seat of the shoe, one of said securing devices being provided with a recess having inclined walls and a conical wedge in the recess, the walls of said wedge 50 inclining in the same general direction as the walls of the recess, the other securing device comprising a kerfed boss so as to provide a series of fingers adapted to be wedged in the aforesaid recess for securing the heel 55 to the shoe.

In testimony whereof I hereunto affix my signature.

LANGDON S. BARRON.
